UNITED STATES PATENT OFFICE.

ARNOLD PFAU, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

WATER-WHEEL BUCKET.

1,309,810.

Specification of Letters Patent. Patented July 15, 1919.

Application filed May 11, 1918. Serial No. 234,352.

To all whom it may concern:

Be it known that I, ARNOLD PFAU, a citizen of the United States, residing at Milwaukee, in the county of Milwaukee and State of 5 Wisconsin, have invented a certain new and useful Improvement in Water-Wheel Buckets, of which the following is a specification.

This invention relates generally to improvements in the construction and operation of hydraulic turbines and specifically to an improved construction of double pocket buckets for impulse water wheels of the jet impelled type.

An object of the invention is to provide 15 a water wheel bucket which is simple in construction and efficient in operation. Another object of the invention is to provide an efficient bucket for water wheels of the type in which it is desirable to deliver unequal quantities of water from the opposite 20 sides of the wheel. Still another object is to provide means for producing lateral or side thrust upon a turbine rotor of the impulse type. A further object is to provide 25 an efficient bucket especially applicable to water wheels of the vertical shaft impulse type.

While the invention is especially adapted 30 for application to jet impelled impulse water wheels having vertically disposed shafts, it is also applicable to turbines of other types having shafts which are otherwise than vertically disposed, in which it is either desirable to discharge different quantities of working fluid from opposite sides 35 of the rotor, or in which it is desired to produce an end thrust upon the rotor by the pressure of the working fluid.

As applied to vertical shaft impulse 40 water wheels the specific objects of the invention are, first to provide a bucket which will produce a turbine of high efficiency by reducing to a minimum the quantity of water dropping upon and against ineffective 45 portions of the rotor after leaving the buckets, and second to provide a bucket which will produce an upward thrust on the wheel tending to counterbalance the weight of the rotor and of the associated parts in order to 50 relieve the thrust bearing pressures. These objects are accomplished by forming the upper pockets of the horizontal annular series of buckets, smaller and shallower than the lower pockets and dividing each bucket

into pockets by means of a ridge or jet 55 splitter. One or more jets are directed against the buckets with their axes below the plane of the dividing ridges, thereby causing more of the water of each jet to impinge within the larger pockets than impinges within the smaller pockets. In this manner the quantity of water delivered upwardly from buckets may be made considerably less than that which is downwardly discharged, without undesirably unbalancing 60 the end thrust and sacrificing efficiency, such as would be the case if the entire discharge were in one direction only. By causing the major portion of the jet to impinge against one side surface of the dividing ridge, sufficient end thrust is produced in an upward 65 direction, to counterbalance the weight of the rotating parts and to relieve the thrust bearing pressures.

A clear conception of an embodiment of 75 the invention may be had by referring to the drawing accompanying and forming a part of this specification in which like reference characters designate the same or similar parts in the various views.

Figure 1 is a fragmentary central vertical section through an impulse turbine installation of the vertical shaft type embodying buckets constructed in accordance with the present invention.

Fig. 2 is an enlarged plan view of one of the buckets, showing the relative position of the jet when impinging thereagainst at the most efficient portion.

Fig. 3 is an enlarged transverse section 90 through one of the buckets showing the relative position of the jet when impinging fully thereagainst, the section being taken along the line III—III of Fig. 2 looking in the direction of the arrows.

The installation disclosed in Fig. 1 comprises generally a power house structure 6 provided with a pit of usual form within which is located the water wheel rotor 2. The rotor 2 is secured to the lower extremity 100 of the vertical main shaft 3, to the upper extremity of which an energy absorbing device of any suitable type not shown, may be connected. An annular series of buckets 8 are spaced around and secured to the periphery of the rotor 2, each of these buckets comprising a pair of pockets 9, 10 and ears 11 by means of which the buckets are fas-

tened to the rotor. Adjustable nozzles 7 which may be one or more in number, are arranged tangentially of the rotor 2 and are adapted to deliver horizontal jets 15 of water against the buckets 8. The vertical main shaft 3 is supported against lateral displacement by means of one or more main bearings 4 mounted upon a main frame 5. The weight of the rotor 2, shaft 3 and the associated parts is borne by one or more thrust bearings 17 of usual construction, associated with the shaft either at the position shown or adjacent to the upper or lower ends thereof.

15 The upper pockets 9 of the buckets 8 are made smaller and shallower than the lower pockets 10 thereof, as shown in Figs. 2 and 3. The pockets 9, 10 of each bucket are separated by a splitter or dividing ridge 12, 20 the ridges 12 of the successive buckets 8 lying in substantially the same horizontal plane. The front portions 13, 14 of the buckets extend beyond the front end of the ridge 12 so that the buckets will more efficiently enter the jets 15. The axes 16 of the jets 15 are below the plane of the dividing ridges 12 as shown in Fig. 3, so that the major portion of the jet 15 impinges within the lower larger pockets 10.

30 During normal operation of the turbine the nozzles 7 are adapted to deliver jets 15 of water moving at high velocity, tangentially toward the runner 2. As these jets 15 strike the advancing buckets 8, they are divided into two portions by the ridges 12, 35 one portion sweeping upwardly through the pockets 9 and the other downwardly through the pockets 10. Due to the formation of the pockets 9, smaller and shallower than the pockets 10, and the location of the jet axis 16 within the region or path of travel of the larger pockets 10, a considerably smaller quantity of water will pass through the buckets 9 than passes through the buckets 10. The water delivered from the pockets 9 drops back toward the wheel, some of the falling water being unavoidably delivered against the rotor 2. The water delivered from the lower pockets 10 is delivered 50 by gravity to the tail race.

By forming the upper pockets smaller, the quantity of water which is upwardly delivered and which falls back against the wheel, is considerably less than with the old 55 type of bucket wherein the pockets were of equal size and the jet was delivered with its axis in the plane of the dividing splitter. By locating the jet axis 16 as shown, the pressure of the jet 15 against the lower surfaces of the ridges 12 produces an upward thrust against the water wheel rotor 2, this thrust approximately balancing the weight of the rotating parts and thereby relieving the pressures upon the thrust bearing 17. 60 The location of the jet 15 should, however,

be such that with the nozzles 7 adjusted to produce a jet of minimum effective size, some water will still be delivered into the smaller pockets 9. With such disposition of the jet maximum efficiency results as the 70 maximum available working area of the buckets is thereby utilized at all times.

It should be understood that it is not desired to be limited to the exact details of construction shown and described as obvious modifications will occur to a person skilled in the art.

It is claimed and desired to secure by Letters Patent:

1. A water wheel bucket having at least 80 two pockets located side by side in a direction longitudinally of the wheel axis, one of said pockets being larger than another.

2. A water wheel bucket having at least 85 two pockets located side by side in a direction longitudinally of the wheel axis, one of said pockets being deeper than another.

3. A water wheel bucket having at least 90 two ovoid pockets separated by a dividing ridge lying in a plane perpendicular to the wheel axis, one of said pockets being larger than another.

4. A water wheel bucket having at least 95 two ovoid pockets separated by a dividing ridge lying in a plane perpendicular to the wheel axis, one of said pockets being deeper than another.

5. A water wheel bucket having at least 100 two ovoid pockets separated by a dividing edge, the front portions of the bucket being extended beyond the front end of said edge as viewed in the direction of the entering jet, and one of said pockets being larger than another.

6. A water wheel bucket having at least 105 two ovoid pockets separated by a dividing edge, the front portions of the bucket being extended beyond the front end of said edge as viewed in the direction of the entering jet, and one of said pockets being deeper than another.

7. In combination, a water wheel having buckets each provided with a pair of pockets of different sizes, and means for delivering a jet of water in unequal proportions to 115 said pockets.

8. In combination, a water wheel having buckets each provided with a pair of pockets of different depths, and means for delivering a jet of water in unequal proportions to 120 said pockets.

9. In combination, a water wheel having buckets provided with substantially aligned dividing edges, and means for delivering a jet of water against said buckets, the center-line of said jet being at one side of the plane of said edges.

10. In combination, a water wheel having buckets each provided with pockets of different sizes, the larger pockets of said buck- 130

- ets being in circumferential alinement, and means for delivering a jet of water against said buckets so that the major portion of said jet impinges within said larger pockets.
- 5 11. In combination, a water wheel having buckets each provided with pockets of different sizes, the smaller pockets of said buckets being in circumferential alinement, and means for delivering a jet of water against said buckets so that the minor portion 10 of said jet impinges within said smaller pockets.
- 10 12. In combination, a water wheel rotatable about a vertical axis and having buckets 15 provided with alined dividing edges, and means for delivering a jet of water against said buckets, the axis of said jet at the point

of impingement being below the plane of said edges.

13. In combination, a water wheel having 20 buckets provided with dividing edges all of which lie in a horizontal plane, and means for delivering a jet of water against said buckets, the axis of said jet at the point of impingement being below said plane. 25

14. In combination, a water wheel having buckets each provided with pockets of different sizes, and means for delivering quantities of water to said pockets proportionate to their sizes. 30

In testimony whereof, the signature of the inventor is affixed hereto.

ARNOLD PFAU.
